The ornamental design for a combined checkbook and information register, as shown and described.

DESCRIPTION

FIG. 1 is a top plan view of a combined checkbook and information register as shown in FIG. 2 in a fully opened position, with the printed inserts omitted for clarity of illustration;

FIG. 2 is a top plan view of a combined checkbook and information register in a fully opened position showing my new design;

FIG. 3 is a top plan view thereof, with the bottom flap closed, it being understood that the undisclosed bottom two thirds is flat and plain;

FIG. 4 is a side elevational view thereof, in a partially opened position, the undisclosed side being a mirror image; and,

FIG. 5 is a side elevational view thereof, in a fully closed position, the undisclosed side being a mirror image.

The top transparent flap in FIGS. 1 and 2 is shown broken away to represent an indeterminate length.
